UNITED STATES PATENT OFFICE.

THOMAS A. RHODES AND WILLIAM H. RHODES, OF PAYNEVILLE, KY.

SPRING FOR BED-BOTTOMS.

SPECIFICATION forming part of Letters Patent No. 252,701, dated January 24, 1882.

Application filed October 15, 1881. (No model.)

To all whom it may concern:

Be it known that we, THOMAS A. RHODES and WILLIAM H. RHODES, citizens of the United States, residing at Payneville, in the county of Meade and State of Kentucky, have invented a certain new and useful Improvement in Springs for Bed-Bottoms; and we do hereby declare that the following is a full, clear, and exact description of the construction of the same, reference being had to the accompanying drawing, forming part of this specification.

Our invention consists in certain improvements in what is known as a "twin bed-spring," a sample of which class of springs is shown and described in United States Patent No. 218,983, dated August 26, 1879, granted to Daniel Kellogg; and the object of our invention is to produce a spring which can be more readily manufactured and bent or shaped by the most simple mechanism in common use.

Referring to the drawing herewith, which illustrates a twin spring embodying our improvement, B B represent the terminals of the two coils A A, of usual construction. These terminals are left straight for insertion through holes in the slats in usual manner, and, like the coils A A, form no part of our present invention.

The connecting portion C consists of an integral length of wire disposed to serve not only as a connecting medium for the springs, but to sustain over an area substantially equal in width and breadth to that of each spring any weight or pressure applied thereon; but we do not claim such connections, broadly, nor do we claim anything shown or described in said Kellogg's patent above mentioned, because our invention relates to a matter subsidiary to that of a connecting portion adapted to act as above stated.

It will be observed that the connecting portion C is formed by disposing the material in parallel lines terminating and merging into free gradual curves, the object being to preserve the width and breadth of supporting area, and at the same time secure such curva-

ture in the material as will not require movable devices to form the same.

It will be observed that in the case above mentioned the curvatures of the connecting portion are all abrupt, the loops are rounded, and practically no straight lines exist therein.

In the manufacture of this class of springs, either before or after the coils are formed, the central portion is bent about around and between guides or dies, and while so placed or bent the natural elasticity of the wire causes it to bend or spring firmly in opposition to the dies, and where said dies, around which the loops are formed, are oppositely arranged this bending requires either movable dies or the application of considerable force to remove the wires therefrom, which usually results in the necessity of "touching up" or reshaping the wires by hand or other machinery.

In the form of spring connection shown by us the loops are simply half-circles joined by straight lines, and the connection is easily removed from the dies, and requires no subsequent touching up or reshaping, and experiment and experience in the manufacture of said class of springs, as shown in the said Kellogg patent, have demonstrated a reduction in the expense thereof.

We do not claim broadly the curves joined by straight lines as of our invention; but

What we do claim as new, and wish to secure by Letters Patent, is—

As an article of manufacture, the twin bed-spring herein shown and described, consisting of the two oppositely-coiled springs A A, provided with the straight depending terminals B B, and with the connecting portion C, disposed in straight lines terminating in semi-circular curves lying within the lateral extent of the upper coils of each spring, as shown and described.

THOMAS A. RHODES.
WILLIAM H. RHODES.
